FREDERICK W. CASE AND WILLIAM H. BURNWORTH, OF COLUMBIA CITY, INDIANA.

MOLD.

1,106,625.

Specification of Letters Patent.

Patented Aug. 11, 1914.

Application filed March 3, 1913. Serial No. 751,801.

To all whom it may concern:

Be it known that we, FREDERICK W. CASE and WILLIAM H. BURNWORTH, citizens of the United States, residing at Columbia City, 5 in the county of Whitley and State of Indiana, have invented certain new and useful Improvements in Molds; and we do declare the following to be a full, clear, and exact description of the invention, such as will 10 enable others skilled in the art to which it appertains to make and use the same.

This invention relates to improvements in molds and particularly to molds for forming concrete staves, blocks or the like.

15 One object of the invention is to provide a mold of this character provided with means for forming staves or blocks having matched edges which when the staves or blocks are brought into operative engagement form a 20 close interlocking joint between the staves.

Another object is to provide a mold comprising separable sections adapted when unfastened to be readily disengaged and removed from the finished staves or blocks and 25 having means whereby the sections are securely fastened together to form the mold.

With these and other objects in view, the invention consists of certain novel features of construction, and the combination and arrangement of parts as will be more fully described and claimed.

In the accompanying drawings; Figure 1 is a perspective view of our improved mold; Fig. 2 is a horizontal sectional view thereof 35 taken immediately above one of the fastening devices for the mold sections; Fig. 3 is a top plan view of the mold showing the same arranged for forming staves or blocks and having tongued and grooved edges; 40 Fig. 4 is a vertical sectional view taken on the line 4—4 of Fig. 2; Fig. 5 is a detail perspective view of a portion of one of the sections of the mold showing the stationary members of the fastening devices; Fig. 6 is 45 a similar view of the clasp or movable member of the fastening devices of the mold sections.

In the present embodiment of the invention the mold is shown as comprising two 50 segmental or slightly curved plates 1 and 2. The plates 1 and 2 correspond substantially in size and shape as shown. One end of the plate 1 is curved laterally to form a hook shaped flange 3 while a similar flange 4 is formed on the adjoining end of the section or plate 2, said flange 4 being of slightly

less curvature than the flange 3 into which said flange 4 is adapted to fit. The overlapping or engaged flanges 3 and 4 of the sections or plates 1 and 2 form this end of the mold. The opposite end of the mold is formed by a substantially U-shaped member 5 having a curvature corresponding to the curvature of the inner flange 4 at the opposite end of the mold, said member 5 being arranged between the ends of the plates or sections 1 and 2 opposite to the ends having the flanges 3 and 4 and when thus arranged the curved or rounded portion of the member projects inwardly as shown. The curved flanges 3 and 4 not only serve to form this end of the mold but also serve to fasten this end of the plates 1 and 2 together in operative engagement for forming the mold. The opposite end of the plates 1 and 2 are detachably fastened together and into engagement with the end forming member 5 by suitable fastening devices arranged near the upper and lower edges of the mold as shown. Each of the fastening devices comprises a stationary member or keeper 6 and a hinge member or hasp 7. The stationary member or keeper 6 is formed by extending this end of upper and lower transversely disposed cleats 8 and 9 which are secured to the outside side of the plate or section 1 of the mold by rivets or other suitable fastening devices as shown. In the upper edges of the keepers 6 formed by the projecting ends of the cleats 8 and 9 are notches 10 with which are engaged the free ends of the hasps 7, the engaging edges of which are also provided with notches 11 whereby an interlocking connection is provided between the hasps and the keepers. The hasps 7 are provided at their opposite ends with eyes 12 which are engaged between and are disposed in alignment with pairs of eyes 13 formed on the adjacent end of upper and lower transverse cleats 14 which are riveted or otherwise rigidly secured to the outer side of the plate or section 2 of the mold as shown. With the eyes 12 and 13 engaged a pivot pin or pintle 15 whereby the hasps 7 are hingedly attached to the cleats 14. When thus arranged the hasps 7 are adapted to be swung across this end of the mold and the notched edge of the hasps engaged with the notches 10 in the keepers 6 as clearly shown in Fig. 1 of the drawings. It will be understood that the engagement of the curved opposite ends of the side plates of the mold will allow

either of these plates to be readily shifted vertically thus permitting the hasps 7 to be swung into position as above described without striking the ends of the cleats 8 and 9 which form the keepers of the hasps. After the hasps have been swung into operative position, the side plates 1 and 2 may be again adjusted to proper positions and the notches 11 in the hasps engaged with the notches 10 in the keepers as described. The hasps 7 are held against casual disengagement from the keepers 6 by hand levers 16 having on their inner ends cam heads 17 which are pivotally secured to one side of the free ends of hasps 7 in position to be forced into engagement with the outer sides of the keepers 6 and when the handles 16 are swung downwardly as shown the cam head 17 will tend to draw one wall of notch 11 against the adjacent inner face of the end of the keeper 6, thus causing a binding frictional engagement between said parts. This construction it will be seen greatly reduces the tendency of the hasp 7 becoming disengaged from its keeper and takes care of wear and a loose engagement of the notches 10 and 11.

When the mold is constructed and arranged as herein shown and described it will be seen that the curved flanges 3 and 4 which form one end of the mold will form a rounded edge on the stave or block at this end of the mold while the curved member 5 at the opposite end of the mold will form a groove in this edge of the stave or block so that when the staves are brought into operative engagement the rounded edge of one stave will fit into the recessed edge of the adjoining stave as will be readily understood. In order to form the staves with tongued and grooved edges, mold blocks 19 and 20 are provided. The block 19 has in its inner edge a longitudinal channel or recess 21 which forms the tongue on this edge of the stave and said block 19 has its outer edge rounded as at 22 to engage and fit into the curved flange 4 of the plate 2 at this end of the mold. The block 20 which is disposed in the opposite end of the mold has on its inner edge a rib or tongue 23, which forms the groove in this edge of the stave. The block 20 has its outer edge recessed to conform to the curvature or rounded surface of the spacing member 5 which forms this end of the mold as clearly shown in Fig. 3 of the drawings. When the blocks 19 and 20 are constructed and arranged as herein shown and described it will be seen that the staves will be somewhat narrower than those formed in the mold without the blocks 19 and 20 and that the staves formed with said blocks will have on one edge a tongue and in the opposite edge a groove so that when these staves are arranged in position for use the tongue and grooved edges thereof will form a close interlocking

joint. After the staves have been molded and sufficiently set the hasps 7 are disengaged from their keepers and this end of the mold sections of plates 1 and 2 thus released. After this end of the plates has been released the opposite flanged ends thereof are disengaged from each other and from this end of the staves and the plates or sections 1 and 2 are then removed from the molded stave without disturbing the latter which is allowed to stand and harden. In order to facilitate the removal of the plates or sections 1 and 2 from the molded stave the upper cleat 8 of the section 1 and the upper cleat 14 of the section 2 are extended beyond the flanged ends of the sections or plates to form handles 24 which may be grasped by the operator and the sections or plates 1 and 2 thereby readily handled.

In forming or molding the staves the latter may be provided with any suitable reinforcement which is embedded therein in the usual manner. It will also be obvious that while the mold has been shown and described for forming staves for use in building silos or other cylindrical structures, it is obvious that the sections or plates of the mold may be shaped differently from that shown in the present instance and the mold employed for forming blocks of other shape, and by employing cores, door, window, or other open frames may be formed in the mold.

From the foregoing description taken in connection with the accompanying drawings, the construction and operation of the invention will be readily understood without requiring a more extended explanation.

Various changes in the form, proportion and the minor details of construction may be resorted to without departing from the principle or sacrificing any of the advantages of the invention as claimed.

Having thus described our invention, what we claim is:

1. A mold of the character described comprising side plates having on one edge curved laterally projecting flanges adapted to be engaged to form an interlocking connection for these ends of the plates and whereby this edge of the block formed in the mold is rounded, a spacing member comprising a substantially U-shaped plate arranged between the opposite ends of the side plates whereby a curved groove is formed in this edge of the molded block, upper and lower cleats secured to the outer sides of said side plates, the cleats of one of said plates projecting beyond one edge thereof and having therein notches adapted to form keepers, hasps hingedly connected to the adjacent ends of the cleats of the opposing plate and having therein notches adapted to be engaged with the notches in said keep-

ers whereby this end of the mold is fastened and cam levers pivoted to the free ends of said hasps and adapted to be swung downwardly into operative engagement with the 5 keepers whereby the hasps are held against casual disengagement from the keepers.

2. A mold of the character described comprising side plates, curved laterally projecting flanges formed on one end of the latter 10 for interlocking engagement, a closing member interposed between the opposite ends of said plates, upper and lower cleats secured to the outer sides of said plates, the cleats on one of said plates projecting beyond one 15 edge thereof and having therein notches, hasps hingedly carried by the contiguous ends of the cleats on the companion plate

and having therein notches for engagement with those in said cleats, and cam levers pivotally mounted on the free ends of said hasps, whereby to be swung downwardly and into frictional engagement with the 20 keepers when the hasps are in operative position to avoid accidental disengagement of the latter.

In testimony whereof we have hereunto set our hands in presence of two subscribing witnesses.

FRED W. CASE.

WILLIAM H. BURNWORTH.
